FEED WHEEL

Howard P. Arnold, Rockland, Mass.

Application October 9, 1936, Serial No. 104,911

1 Claim. (Cl. 74—230.8)

This invention relates to a pulley-like structure such as is used for feed wheels or tension wheels, and particularly to feed wheels or tension wheels of the type in which the peripheral groove for receiving the strand, cord or the like is formed by two series of radially-extending arms with the arms on one side of the groove having a staggered relation to the arms on the other side of the groove.

10 One of the objects of the invention is to provide a novel feed wheel of this type which is simple in construction and which can be inexpensively manufactured and also to provide a feed wheel having a rim on each side of the groove integral with the arms.

20 My improved feed wheel or tension wheel is made from two similar disk-like members of sheet material, each having a central body portion and a plurality of arms extending outwardly from the body portion in radial directions and a rim portion connecting the ends of the arms, the body portion, arms and rim portion of each member being integral with each other. The two members are assembled with the body portions thereof in registering engagement, and the arms 25 of each member are so shaped that a portion of each arm of each disk-like member enters a space between two adjacent arms of the other disk-like member so that the arms of the two disk-like members have a crossing relation. The 30 outer ends of the arms of each member flare outwardly and the rim portions of each member also flare outwardly, whereby the pulley is provided with a peripheral V groove with interrupted side walls, each side wall having openings opposite the solid portions of the other wall.

35 In the drawing wherein I have shown a selected embodiment of the invention;

Fig. 1 is a view of one of the disk-like feed wheel members;

40 Fig. 2 is a view of the other feed wheel member;

Fig. 3 is a side view of the two members assembled to make the complete feed wheel;

45 Fig. 4 is a section on the line 4—4, Fig. 3.

50 My improved feed wheel comprises the two similar members 1 and 2, each of which is stamped out from sheet material, preferably sheet metal. Each member comprises a central portion 3 having a plurality of arms 4 radiating therefrom, and a narrow, continuous rim section 5 integral with the arms and connecting the outer ends thereof. Each arm 4 of each member is deformed by being bent laterally as indicated 55 at 6, thereby forming a shorter arm section 14

which connects to the central portion 3 and inclines in one direction relative to the plane thereof and a longer arm section 15 making an angle with the shorter arm section 14 and which inclines in the opposite direction relative to the plane of the central portion. The arms of each member are spaced from each other by a distance slightly greater than the width of the arms of the other member and the two members 1 and 2 are assembled with the central portions 3 of the two members in registering relation, as shown in Fig. 4, and with the offset portion 6 of each arm of one member occupying the spaces 7 between the arms of the other member, as best seen in Fig. 4. With this arrangement the arms 15 of the two members have a double crossing relation, the shorter arm sections 14 of one member crossing those of the other member and the longer arm sections 15 of each member likewise crossing those of the other member. This crossing relation of the longer arm sections 15 forms a V groove 8 having interrupted side walls, each side wall having openings formed by the spaces 7 in the disk-like members and the openings in each side wall being opposite the solid portions of the other side wall formed by the arms 4. The V groove thus provided has the solid portions of its two walls in staggered relation so that when a cord or strand is laid in the groove it will assume a sinuous course whereby there is provided an excellent gripping or frictional engagement 20 between the wheel and the cord. The narrow continuous rim sections 5 have the advantage that they facilitate the feeding or laying of the cord in the groove.

25 The two members 1 and 2 may be secured together in their assembled relation in any suitable way. As herein shown these members are mounted on a hub 10 which is adapted to be secured to a shaft or other support. This hub is 30 shown as having one end 11 reduced in diameter and the central portions 3 of the members 1 and 2 are provided with a central opening 12 of a size to fit over the hub portion 11 of reduced diameter. The end of the portion 11 of the hub is 35 shown as spun over slightly, as indicated at 13, thereby locking the two wheel members in place. These wheel members, however, might be spot-welded together or secured together in any desirable way.

40 The complete feed wheel is thus made up of two similar sections which when assembled provide a V groove having smooth edges, but with the arms 4 of the two members having a staggered crossing relation which, as stated above, 45

causes the cord or strand which is laid in the groove to assume a sinuous course.

A wheel or pulley embodying my invention is well adapted for a feed wheel for feeding a strand or cord forward since the smooth continuous rim sections 5 facilitate the laying of the cord or strand in the groove and the staggered crossing relation of the arms provides a groove which affords an excellent frictional grip on the cord for feeding it forward.

A wheel embodying my invention is also well suited for use as a tension wheel.

I claim:—

A feed wheel comprising two similar disk-like members of sheet material, each having a central portion, spaced arms extending radially from the central portion, and a narrow continuous rim portion connecting the ends of the arms, each arm being bent to present a shorter inner arm

section connected to the central portion and inclining in one direction relative to the plane thereof and a longer outer arm section connected to the rim portion and which inclines in the opposite direction relative to the plane of the central portion and thereby makes an angle with the shorter arm section, said disk-like members being assembled with the central portions in registering engagement and with the apices of the bent portions of the arms of one member occupying the spaces between the arms of the other member, and with the longer outer arm sections of the two members having a crossing relation and forming between them a V groove having interrupted side walls, each side wall having openings opposite the solid portions of the opposite side wall.

HOWARD P. ARNOLD.
